UNITED STATES PATENT OFFICE.

CHARLES A. PORT, JOHN E. O'NEAL, AND DORACE E. MOTZ, OF PAGOSA SPRINGS, COLORADO.

GASOLENE-FILTER.

1,032,240.

Specification of Letters Patent.

Patented July 9, 1912.

Application filed April 10, 1912. Serial No. 689,883.

To all whom it may concern:

Be it known that we, CHARLES A. PORT, JOHN E. O'NEAL, and DORACE E. MOTZ, citizens of the United States, and residents of 5 Pagosa Springs, in the county of Archuleta and State of Colorado, have invented an Improvement in Gasolene-Filters, of which the following is a specification.

Our invention is an improvement in gaso- 10 len filters for use with the carbureters of gas motors, especially such as are used on automobiles.

The invention is embodied in the construction and combination of parts herein- 15 after described and illustrated in the accompanying drawing, in which—

Figure 1 is a vertical section of the apparatus. Fig. 2 is a transverse section on the line 2—2 of Fig. 1.

20 A indicates a gasolene receptacle which is constructed substantially like the receptacle shown and described in our companion application for Letters Patent for gasolene filter, Serial No. 672,036. That is to say, 25 the receptacle A comprises a glass cylinder 1 whose upper end abuts a flanged head 2, and screw bolts 3 pass through this head, exteriorly of the cylinder 1, and are screwed into the upper annular edge of a water-re- 30 ceiver B, the same being provided with an internal shoulder 4 upon which the glass cylinder rests, suitable packing 5 being interposed in order to insure a tight joint. A supplemental or auxiliary water receptacle 35 C is detachably connected with the water- receiver B, by means of pipes 6, 7, and 8 which are screwed together, and also by a pipe D which is arranged above the auxiliary tank and also detachably connected 40 with the water-receiver. The auxiliary tank C is located below and at one side of the water-receiver. A gasolene discharge pipe E passes up centrally through the bottom of the water-receiver B and is screw-threaded 45 at that point, so that it may be adjusted higher or lower. The upper end of the pipe E reaches about the center of the glass cylinder 1, and is inclosed by a filter proper F, which, as in our former invention above re- 50 ferred to, is constructed of a rigid wire frame, a wire gauze screen for the same, and a chamois covering applied outside the screen and secured at the lower edge of the filter to a collar attached to the pipe E. A

protector F^a is applied over the filter F as 55 in our former invention. Directly below the filter F there is applied and secured a filter guard G which is constructed of sheet metal and made in the form of an inverted funnel; that is to say, the larger end of the 60 truncated cone being lower and arranged just below the point where the glass cylinder 1 is supported on the shoulder 4 of the water-receiver B. The guard G being attached to the discharge tube E is adjustable 65 vertically therewith and by such adjustment may be brought nearer to or farther from the inner shoulder 5 of the water-holder B, so that it may be adjusted to close the annular passage more or less, as required to 70 effectually prevent water splashing upward into the gasolene receptacle and thus reaching the filter. A jam nut 11^a is applied to the threaded portion of the pipe E for holding it fixed in any vertical adjustment. 75

It will now be understood that gasolene delivered into the receptacle A through the feed pipe 11 discharges upon the protector F^a and gradually fills the receptacle, the water-receiver B, and the auxiliary tank C 80 and the connecting pipe D. Said tank and pipe D are not used under ordinary conditions, but only in case the gasolene contains an unusual amount of water, and they, to wit, the parts C and D, are made easily detachable from the primary water-receiver B. It is obvious that the openings in the water-receiver B will be plugged when the tank C and pipe D are detached. When the tank C is used, water, owing to its gravity, 85 will first accumulate therein and will crowd the gasolene up through the pipe D from which it will discharge into the water-holder B and mingle with the general body of gasolene and thus find its way through 90 the filter. The tank C is provided with a drain cock 12 for drawing off water and sediment. A similar cock 13 is applied to the water-holder B. The gasolene receptacle A is provided at the top with an air 95 valve 14.

What we claim is:—

1. In a gasolene filter, the combination with a gasolene receptacle and a water holder arranged below and communicating therewith, of a gasolene filter and discharge pipe projecting upward into the gasolene receptacle, and an inverted funnel-shaped 105.

filter guard arranged below the same, its larger end being lowermost, substantially as described.

2. The combination with a gasolene receptacle and a water holder having an interior shoulder and arranged below and communicating therewith, of a filter and a gasolene discharge pipe to which it is attached, said pipe passing down through the 10 water receptacle and adapted for vertical

adjustment, and a filter guard attached to the pipe below the filter, its outer edge being adjacent to the said shoulder of the water holder, substantially as described.

CHARLES A. PORT.
JOHN E. O'NEAL.
DORACE E. MOTZ.
